UNITED STATES PATENT OFFICE.

FRANK WILCOMB, OF PROVIDENCE, ASSIGNOR TO WM. H. HASSELL, OF PAWTUCKET, RHODE ISLAND.

STRAIGHT-KNITTING MACHINE.

SPECIFICATION forming part of Letters Patent No. 463,560, dated November 17, 1891.

Application filed June 13, 1891. Serial No. 396,170. (No model.)

To all whom it may concern:

Be it known that I, FRANK WILCOMB, a citizen of the United States of America, residing at Providence, in the county of Providence and State of Rhode Island, have invented certain new and useful Improvements in Straight-Knitting Machines, of which the following is a specification.

My invention relates particularly to straight-latch-needle knitting-machines designed to knit a tubular fabric and automatically shape the same; and it includes mechanism for introducing new needles in such a manner for widening the fabric as will cause the crossing of the thread to prevent the formation of holes in the fabric where the new needles are brought into action.

It includes the particular operating mechanism by which the needles are controlled in their movements to cross the thread at the ends of the rows when knitting plain, in order to form a mock seam in the fabric to imitate regular fashioned goods.

It includes, further, a special form of non-reversible thread-carrier for feeding first one row of needles and then the other.

In the accompanying drawings, Figure 1 is a front view of the machine with parts broken away. Figs. 1^a and 1^b are views of details. Fig. 2 is a plan view with parts removed and parts in section. Fig. 3 is a transverse section through the upper part of the machine. Figs. 4, 5, and 6 represent, respectively, a front, a plan, and a sectional view of the thread-guide. Fig. 7 is an end view of the machine, partly in section. Fig. 8 is a bottom plan view of the cam-bar. Fig. 9 is a plan view of the upper face of the cam-bar. Fig. 10 is a rear view of the bar. Figs. 11, 12, 13, 14, and 15 represent in diagrammatic form the needles and the notched slides controlling the same.

The needles *a* are operated through jacks *b* from cam-bars *A*, which are reciprocated through connections to the cam-shaft, consisting of the lever *B*, pivoted to the frame at 1, Fig. 1, and loosely connected by a pin and depending fork 3 to a cross-head 4, to which the cam-bars are attached. The cross-head slides on a bar 5, projecting from the end of the machine, and which is sustained by a bracket 6, projecting from the machine-frame and shown

broken off in Fig. 1. The lever *B* is connected by a pitman 2 to a cam or face wheel *x* on the cam-shaft *C*. This is driven from the main shaft *D* by a pinion 7 and a gear 8. The nibs 55 of the jacks *b* travel in the cam-groove 10, Fig. 8, and unless the jacks are pushed forward, so that the nibs will engage with the inclined portions of the stitch-cam 11, the jacks and needles will remain inactive, and for the purpose of 60 this invention it is intended that first one row of jacks and needles shall remain inactive and then the other. For moving the jacks with their needles to engage the stitch-cams a second set of jacks *c* is employed under tension 65 of springs 12. These jacks are held normally in retracted position against the tension of the springs by notched slides *E F* working in the notches 13 of the jacks; but when either slide is moved so that the notches thereof 70 align with the jacks all the jacks on that side are released and are free to move forward when the inclined supplemental cam-groove 14 comes opposite them and in their upward movement, which takes place in succession, 75 these jacks of the lower set strike those of the upper set and move them into the stitch cam-groove 11 for the ordinary knitting operation. The upper nibs of the lower jacks ordinarily (or while inactive) are slightly off 80 the lower face of the cam-bar, thus preventing friction, and when the jacks are released to be pushed forward by the springs these nibs enter the supplemental cam-groove when it arrives at that point. The notches of the 85 opposite controlling-slides *E F* alternate in position, the notches of the slide on one side being opposite the teeth in the other slide, so that the jacks with their needles are released on one side, while those on the other side are 90 held by the teeth of the slide on that side. The slides shift their position at the end of the cam-bar's stroke in either direction to effect the alternate release of the opposite row of needles, and this shifting movement in knitting plain goes on regularly and is secured by a lever *d*, pivoted in a slotted bracket 15, one end having a roller acted on by a cam *x*, and the other end engaging a circumferential groove in a collar 17, fixed on a screw-shaft 100 *e*. This shaft has longitudinal movement by means of the lever and cam in one direction,

and it is returned to its outward position by a spring 18, within a hollow bearing-stub 19, which has a conical bearing-point. The outer end of the screw-shaft moves in a bearing on the bracket 15. The notched slides are connected to a cross-head G, movable on the bracket 15, and the longitudinal movement of the screw-shaft is imparted to this cross-head through a nut f, which is detachable from the shaft for a purpose hereinafter described. The amount of movement of the slides either way is equal to one-half the distance from needle to needle, and by reference to Figs. 11 to 15 it will be seen that at the end of the rows of regular notches in the slide E a tooth 20^x of double width is formed, while opposite in the slide F a notch 21^x of double width is formed, and next to the double tooth in the slide E an additional small notch 20 is formed. This construction is provided in order to permit crossing the thread at the ends of the rows in widening the fabric to prevent the formation of holes, and also to cross the thread at the end of the needle-rows in plain knitting. Suppose sixty-one needles in each row are being used, then when the slides are in the position of Fig. 11 all the needles of the front row, (or that controlled by the slide E,) excepting the end needle 61, are active and the thread is taken by these needles successively, while the needles in the back row, excepting the end needle 61 in the wide notch 21^x, are all inactive. The thread therefore misses the needle 61 of the front row and crosses to the needle 61 of the back row. The slide then shifts, as in Fig. 12, and on the return of the carrier the thread is taken by the needle 61 of the front row and then crosses to needle 60 of the back row, and along said row to the end, and when the thread-carrier reaches the left the slides shift back to the position of Figs. 11 and 13, and the operation of crossing and recrossing the threads is repeated. When the shaping of the fabric begins, the slides, after returning to the position of Fig. 13, do not shift to the left, as above explained; but at the end of the right-hand stroke of the machine they are given an additional movement to the right, as in Fig. 14, thus bringing into action a new needle 62 of the front row, and the thread is then looped about this as the carrier returns to the left and then crosses to back needle 61 and along the back row. At the next course the slides move again to the right, as in Fig. 15, rendering the front needles (opposite the notched portion of the slides) active, excepting needle 62, and bringing in a new back needle 62, the thread crossing to the said back needle at the end of the course. Two new needles are thus brought into action—one in each row—and the slides shift to the left for knitting any desired number of plain courses, as first explained, with the needles 62, the fabric being widened by two new wales and the thread being crossed and recrossed to close the openings ordinarily left by the new needles. This widening movement

of the slides is affected by the rotation of the screw-shaft, which moves the nut and cross-head to the right in excess of the regular longitudinal movement of the screw-shaft and notched slides to the left, and this rotation of the shaft is determined by pattern mechanism. A spring-actuated pawl 21 in the fixed grooved collar 17 is engaged by a toothed rim 22 of a loose pinion 23. A rack-bar 24, under tension of a spring 25, engages the pinion, and a roller 26 on its lower end bears on a cam 27. The rack is held up inactive by a bell-crank lever 28, engaging a pin 29 on the rack-bar, which projects through a slot 30 in the cap-plate 31. When the catch-lever is withdrawn by means of a lug on the pattern-chain 32, raising the lever 33 and drawing upon the rod 34, the spring 25 draws the rack-bar down and turns the loose pinion backward without effect, the spring-pawl being beveled, as shown, to permit this; but when the high part of the cam 27 lifts the rack-bar, the pinion is turned forward and through the notched rim 22 and pawl turns the fixed collar and the shaft, causing the screw-nut f to travel along it and move the cross-head and notched slides. The lever 28 and the pattern-lever 33 are returned to normal position by a spring 70. The nut f is movable vertically between jaws 35 on the cross-head, and is pressed normally upward by a spring 36, and may be detached from the screw by a cam-lever 37, connected thereto by a stem 38, which passes through a portion of the cross-head depending through a slot in the bracket 15. When detached the cross-head with the notched slides may be shifted to their extreme limit to the left after having widened, for beginning a new fabric, and a stop 39 is provided on the screw-shaft to determine the position. The screw-shaft is retained against rotary displacement by a spring-actuated pawl 39, Fig. 1^a, which is seated in the bracket 15, and engages notches in the grooved collar 17. This does not interfere, however, with the free longitudinal movement of the screw-shaft. The pattern-chain passes over a sprocket-drum 39^x, loose on a shaft 43, and this is provided with a ratchet-wheel to which movement is given by a pawl 40, carried by an arm 41, fixed to the shaft 43, which is rocked by a cam 42 through an arm 43^x and a spring 44. A detent 45^x prevents the ratchet and the pattern-chain from retracting.

In order to prevent the entire row of lower jacks when released from bearing upon the lower side of the cam-bar and thus creating friction, a series of dogs 45 are provided, Fig. 3, which engage the nibs of the jacks and hold them back. These dogs have nibs fitting in a cam-groove 46, in the rear side of the cam-bar, and, as shown in Figs. 8 and 10, this groove has a rise opposite the stitch-cam, so that the lower jacks are released from the dogs in succession when the stitch-cam comes in line therewith.

I employ movable sinkers 47, which act to

measure off the yarn for the loops and to hold the web without requiring a weight. These are operated by cam-bars 48, which are connected with the main cam-bars by the 5 curved arms 49.

In order to vary the length of the stitch, I mount the wings 50 of the stitch-cam upon a plate 51, having an enlarged opening to admit the V-cam 52, which is fixed to the bar. 10 The plate 51 may be slid to move the wings closer to or farther from the V-cam, and for this purpose a plate 53, having an inclined slot, is adjustably held, the slot receiving a block 54 on the end of the pin 55 of the plate 15 51. The plate is connected to a bar 56, extending through a bearing 57 on the cross-head of the cam-bar, and this bar is threaded and made adjustable by the nuts 58. These devices for varying the length of the stitch 20 are the same on both sides of the machine.

The thread-guide 59 is composed of a bar extending longitudinally between the needle-rows, having beveled faces forming a knife-edge 60, adapted to open and hold the latches 25 of the needles. A central opening 62 is formed through the guide and its stem 61 for the passage of the thread, and this opening is elongated at its mouth and has inclined ends or corners, as shown, which terminate 30 on opposite sides of the knife-edge, so that in going one way the thread will be directed on one side of the said edge, and in going in the opposite direction it will be directed on the opposite side of the said edge, thus feeding 35 one row of needles and then the other. The thread-guide is supported in an arm 65, pivoted to a standard 66 on one of the cam-bars. The arm is held normally down by a spring 67; but it may be raised, when desired, to lift 40 the guide to permit access to the needles.

The method of knitting disclosed herein and the fabric produced thereby is the subject of an application for United States Patent filed by me of even date herewith, Serial 45 No. 396,171.

I claim as my invention—

1. In combination, the needles, the cam-bars, means for moving the needles into operative position, and the slides acting alternately to lock said means in their inoperative position first on one side of the machine and then on the other, and operating mechanism for the slides, substantially as described. 50

2. In combination, the needles, the cam-bars, means for moving the needles into operating position, the locking-slides to retain the said means inoperative first on one row and then on the other, mechanism for operating said slides to and from their locking position, 55 and devices for giving said slides an additional movement for shaping the fabric, substantially as described.

3. In combination, the needles and cam-bars, means for moving the needles into operative position, a pair of locking-slides having notches arranged to release said means alternately first on one row and then on the 60

other when said notches align therewith, and means for operating the slides in unison, substantially as described. 70

4. In combination with the needles and cam-bars, means for forcing the needles into operative position, the locking and shaping slides having a series of notches alternately set with relation to each other, one of said slides having a wide tooth opposite a wide notch at the end of the other slide and an additional small notch, and the operating means for the slides, substantially as described. 75

5. In combination, the needles, the cam-bars therefor, the jacks and springs for forcing the needles forward into operative position, the slides, with means for operating them to lock and release the jacks alternately, and the holding-dogs for the jacks, the said cam-bars having grooves for operating the dogs, substantially as described. 80

6. In combination, the needles and cam-bars, the means for moving the needles forward into operative position, the notched locking-slides, the cross-head, and the operating connections leading to the main shaft, substantially as described. 90

7. In combination, the needles, the means for moving the needles into operative position, the cam-bars, the locking and shaping slides, the screw-shaft, the connections therefrom to the slides, the means for reciprocating the shaft with the slides, and the mechanism for rotating the screw-shaft to move 95 the slides for shaping the fabric, substantially as described. 100

8. In combination, the needles, means for moving the needles into operative position, the cam-bars, locking and shaping slides, operating mechanism therefor, and a detachable connection between said slides and operating mechanism, substantially as described. 105

9. In combination, the needles, means for moving the needles into operative position, the cam-bars, the locking-slides having a series of notches, the screw-shaft connected to the locking-slides, the means for moving the shaft longitudinally, consisting of the lever and cam, and the means for rotating the screw, 110 consisting of the loose pinion, the pawl, the rack-bar, the cam, the catch-lever for holding the rack inoperative, and the pattern mechanism for withdrawing the catch-lever, substantially as described. 120

10. In combination, the needles, means for moving the needles into operative position, the cam-bars, the locking-slides, the screw-shaft, with means for operating the same, the detachable nut between the shaft and slides, 115 and the stop, substantially as described. 125

11. In combination, the needles and cam-bars of a straight-knitting machine, a thread-carrier arranged over the rows having a knife-edge adapted to open and hold the latches of 130 the needles, and an opening for the thread having a mouth with the opposite ends thereof on opposite sides of the knife-edge, substantially as described.

12. In combination, the needles, means for moving the needles into operative position, the cam-bars, the locking-slides and the shaft for operating the same, the means for moving the shaft in one direction, and the spring-pressed bearing for the end of the shaft, substantially as described.
13. In combination, the needles and cam-bars, the V-cam 52, the wings 50, mounted on a plate 51, and means for adjusting said plate,

consisting of the plate with the inclined slot and the adjustable rod 56, connected to said slotted plate, substantially as described.

In testimony whereof I affix my signature in presence of two witnesses.

FRANK WILCOMB.
